United States Patent

Des. 239,256
Patented Mar. 23, 1976

239,256

CONTAINER END

Richard J. Brincks, Wheeling, William L. Fox, Jr.,
Libertyville, and Henry S. Holc, Barrington, Ill., as
signors to American Can Company

Original design application Aug. 10, 1972, Ser. No.
279,308, now U.S. Patent No. 233,137. Divided and
this application Oct. 1, 1973, Ser. No. 402,600

Term of patent 14 years

Int. Cl. D9—07

U.S. CL. D9—253

FIG. 1

FIG. 2

FIG. 1 is a top plan view of a container end showing our new design, and

FIG. 2 is an enlarged scale cross-sectional view taken along line 2—2 of FIG. 1.

This application is a divisional of application Ser. No. D. 279,308 filed Aug. 10, 1972, now U.S. Pat. Des. 233,137, dated Oct. 8, 1974.

We claim:

The ornamental design for a container end, substantially as shown and described.
